Attorney

UNITED STATES PATENT OFFICE.

JOSEPH SIDNEY REED, OF HOUSTON, TEXAS.

CLEANING DEVICE.

Application filed March 8, 1928. Serial No. 260,105.

The present invention relates to cleaning devices and more particularly to devices of this character for cleaning the mortar from reclaimed bricks, the invention embodying 5 the provision of a rotatably mounted disk adapted to carry a plurality of cleaning pins or prongs extending laterally from the face thereof against which the brick may be held and through the rotary action of the device 10 to scrape and clean the mortar from the brick.

A further object of the invention is to provide means for adjustably mounting the ends upon the disk so that upon the wearing down of the pins, through usage, a suitable adjustment may be made so as to maintain the outer 15 ends of the pins a uniform distance outwardly from the face of the disk.

A still further object is to provide a device of this character of a simple and practical 20 construction, which may be easily and quickly attached and detached to any conventional rotating member, which provides for the renewal of the cleaning ends from time to time as the same become worn, which is relatively 25 inexpensive to manufacture and otherwise well adapted to the purposes for which the same is intended.

Other objects and advantages reside in the special construction, combination and arrangement of the various elements forming 30 the invention as more fully hereinafter described and claimed, reference being had to the accompanying drawings forming part hereof, wherein like numerals refer to like 35 parts throughout and in which:

Figure 1 is a front elevational view of the device, and

Figure 2 is a transverse sectional view taken substantially along a line 2—2 of Figure 1.

Referring to the drawings in detail, the invention comprises a pair of circular disks indicated at 5 and 6 respectively, having a central opening through which a set of attaching bolts 7 may be extended, said bolts having one end threaded and inserted through openings formed in a retaining ring of a diameter slightly larger than the central opening formed in the disk and adapted to be fitted over the opening of the outermost disk, with the opposite end of said bolts formed into hooks 9 adapted for engagement with the spokes 10 of a fly wheel 11 and upon

threading nuts 15 on the outer threaded end of the bolt to secure the disks 5 and 6 against 55 one side of the fly wheel.

The outer disk 6 is provided with a large number of relatively small openings through which cleaning pins 12 extend, the inner ends of said pins having heads 13 formed thereon and disposed in abutting relation with the adjacent face of the innermost disk 5, a relatively small number of said pins being provided with a series of washers or shims 14 interposed between the head of the pins and the inner face of the outer disk 6 whereby to space the disk in parallel relation with respect to each other and so that the outwardly disposed ends of the pin will be maintained a predetermined distance outwardly from 70 the face of said outer disk.

The fly wheel 11 is adapted for rotation in any well known manner, it being obvious that by attaching the disks thereto in the manner indicated that the same will also rotate together with the fly wheel. It will also be apparent that by holding the object to be cleaned, as for instance a reclaimed brick which may be covered with quantity of mortar, against the face of the outer disk being 80 provided with the pins at the rapid sectional movement of the ends of the pins upon the brick will cause the mortar to be removed from the brick.

As the ends of the pins 12 become worn one 85 or more of the washers or shims 14 may be removed so that the pins may always be maintained at a uniform distance outwardly from the face of the disk.

Should the pins become worn to such an 90 extent as to fail to protrude outwardly from the face of the disk the pins may then readily be replaced.

It is obvious that my invention is susceptible to various changes and modifications in 95 construction without departing from the spirit of the invention or the scope of the appended claim, and I accordingly claim all such forms of the device to which I am entitled.

Having thus described my invention, what I claim as new is:

A cleaning device of the class described comprising a pair of disks, an attaching plate, wheel attaching bolts carried by said plate 105 and adapted for securing said disks in

parallel relation against one side of a supporting wheel for rotation therewith, the outermost of said disks having a series of openings formed therein, cleaning pins extended through said openings having heads formed on their inner ends in abutting relation against the innermost of said disks and

a plurality of shims removably carried by the pins and disposed between the disks whereby to regulate the extent at which the pins protrude from the outermost disk.

In testimony whereof I affix my signature.

JOSEPH SIDNEY REED.
